UNITED STATES PATENT OFFICE.

ANDREW HUNTER AND ERNST KUEHNE, OF CHICAGO, ILLINOIS.

FLOUR-DRESSING MACHINE.

SPECIFICATION forming part of Letters Patent No. 278,143, dated May 22, 1883.

Application filed December 26, 1882. (No model.)

To all whom it may concern:

Be it known that we, ANDREW HUNTER and ERNST KUEHNE, citizens of the United States, residing at Chicago, in the county of Cook and State of Illinois, have jointly invented certain new and useful Improvements in Flour-Dressing Machines, of which the following, in connection with the accompanying drawings, is a specification.

10 In the drawings, Figure 1, Sheet 1, is a side elevation of a flour-dressing machine embodying our invention. Fig. 2, Sheet 1, is a longitudinal vertical central section of the same. Fig. 3, Sheet 2, is a vertical cross-section in the plane of the line $\alpha\alpha$ of Fig. 1. Fig. 4, Sheet 2, is a like representation in the plane of the line $\gamma\gamma$ of Fig. 1, and Fig. 5 is a sectional detail of the stationary cylinder.

The same letters of reference indicate the 20 same or corresponding parts.

A represents the frame of the machine, which is adapted to receive and support the working or operative parts suitably.

B is a receiving-hopper, into which the meal 25 is fed. This hopper has a close or tight fitting cover, a , in which is a tube, a' , to permit the air to escape that enters with the meal.

C is a rotary shaft passing horizontally through the hopper B, and b b are radial arms 30 or teeth fitted or applied to the said shaft.

D represents wire-cloth, so hung in the hopper B as to hold the meal up to the action of the teeth b b .

E is a screw-conveyer, arranged horizontally 35 in the bottom of the hopper B and located below the wire-cloth D.

F is a drop-valve, hinged at its upper edge to the inner end, near the bottom portion of the hopper, and swinging outward with relation to the hopper.

G G are magnets arranged in the hopper.

I is a chamber having a hopper-shaped bottom, and J is a stationary hollow cylinder located in the chamber I. The cylinder J consists of annular or segmental ribs c c , attached to cross-bars c' c' , secured to the walls of the chamber I. The cylinder J, therefore, is skeleton in form or open between the ribs c c ; but we close these, the lower openings by means

of canvas c'' and the upper by means of silk 50 bolting-cloth c''' , applied to the cylinder. The cylinder J, as will hereinafter be perceived, performs the function of a bolter, and we make its frame in detachable and interchangeable sections.

K is a rotary shaft passing centrally through the cylinder J, and K' K' are arms extending radially from the said shaft.

L L are horizontal bars or helical beaters attached to the ends of the arms K' K'. The 60 arms K' K' on one end of the shaft K are set a little farther around than those on the other, so as to give a slight degree of spirality or diagonal direction to the beaters L L, as indicated in Fig. 2.

M is a passage or eduction-opening into the cylinder J, and d is an inclined shelf or chute at the upper end of said passage. Near the lower end of the passage M is an outwardly-opening gravitating valve, d' . The drop valve 70 also opens into the cylinder J, as shown.

N is an air-chamber above the chamber I, and N' is an air-pipe entering the chamber N.

O and O' are screw-conveyers arranged below the cylinder J. Between the conveyers O 75 and O' is a partition, e, in which are slides e' e' and an opening, e'' . The slides e' e' are located in openings in the partition e, and these are opened by drawing these slides out and closed by pushing them in.

P are openings in the bottom of the dresser.

Q Q are removable panels in the sides of the dresser.

R is a partition of cloth arranged vertically across the upper part of the chamber I.

S is the driving-pulley.

No fans are used in the flour-dressing machine.

The operation of the parts now described is as follows: The meal is fed into the hopper B 90 and falls upon the wire-cloth D, where the flaky particles and fractured middlings are broken or disintegrated by the teeth or arms b b . The magnets G G catch and hold any small particles of metal that may have entered 95 with the meal. The meal then falls upon the conveyer E, and is carried to and out of the drop-valve F, which is opened by the meal and

only enough to let the meal out, thereby preventing the air from entering into the cylinder J, only that which is contained in the openings in the meal. The only place where air can 5 enter into the cylinder J is through the openings protected by the drop-valves F and d'. The air that enters with the meal finds an easy escape through the tube a', which is located immediately over or above the drop-valve F. 10 The meal which passes out through the drop-valve F falls into the cylinder J, where it is operated upon by the helical beaters L L. The heavy portion of the meal, or that part having a certain specific gravity, is thrown 15 against the covering of the cylinder J, and the fine fluff and impurities, having a certain specific gravity, remain in the center until carried to the tail end by the helical beaters. The fine fluff and that part of the heavy material which 20 is too coarse to pass through the bolting-cloth are lifted up and fall on the shelf d and pass out through the passage M and drop-valves d'. The drop-valve d', like the drop-valve F, opens only enough to permit the tailings to pass out, 25 and thus prevents the entrance of air. The fine heavy part of the contents of the cylinder J is forced through the bolting-cloth and falls upon the conveyer O, by means of which it is carried to the opening e'', where it passes out 30 of the machine. If it is necessary to return a part of the flour, we open one or more of the slides e' e', which allows that portion under the opened slides to fall on the conveyer O' and be conveyed out through the lower opening, e''. The heavy portions of the contents of 35 the cylinder J are thrown out against the silk or the periphery of the cylinder by the centrifugal action of the beaters L L. The air being as nearly as possible excluded from the 40 cylinder, the beaters form a circuitous current around their own circuit of revolution of greater force than the specific gravity of the fluff. Consequently it remains in the center of the circuit until carried to the tail end by the 45 action of the spiral beaters. The beaters operate much the same as they would if rotated in a vacuum. Consequently there is no current of air to carry the fine fluffy material from the center to the periphery and force it through 50 the silk with the flour. If heated air is permitted to remain in the cylinder, it must condense. Consequently the moisture, coming in contact with the flour, will cause a portion of the coloring-matter to adhere to it, as well as 55 softening the flour. By this means the condition and quality of the flour are much improved. The tailings are also cleaner, and the dresser is comparatively compact and requires a comparatively small power to run it. 60 The canvas a'', which covers the bottom of the cylinder, allows the bottom frame of the cylinder to be made light, thereby producing an elasticity or spring movement which causes the silk on the upper sections to keep clean, 65 which otherwise would require brushing if a

solid board or metal bottom were used. The direction of the movement of the beaters L L is indicated by the arrow shown in Fig. 3. The canvas a'' holds the meal until it is carried by the beaters up and against the silk e''' on that side of the cylinder where the movement of the beaters is upward. The silk on this side of the cylinder we make of finer material or finer numbers than that on the other or down side of the beaters. For instance, 70 on the side on which the beaters move upward we use No. 16 bolting-silk, and that on the downward side about No. 12. We find that if the numbers of silk be changed from one side to the other the flour with No. 12 on 75 the lifting side would be dark and specky; the flour on the downward side, if clothed with No. 16 silk, would be soft and greasy. We are well aware that graded cloth has been used; but each grade of numbers extended around 80 the circumference. All dressers that employ a revolving cylinder could receive no benefit from coarse numbers on one side and fine on the other. The only way we could reach satisfactory results was by using comparatively 85 fine silk on the up side and coarser on the downward side. 90

Having thus described our invention, what we claim as new, and desire to secure by Letters Patent, is—

1. The combination, in a flour-dressing machine, of a ventilated hopper and rotating teeth b b with concave wire-cloth D, conveyer E, and trap-door H, substantially as and for the purposes specified. 95

2. The combination, in a flour-dressing machine, of chamber I, the stationary bolting-cylinder J, connecting therewith, a ventilating-chamber in their top, and air-escape tube N', substantially as and for the purposes specified. 100

3. The combination, in a flour-dressing machine, of a stationary bolting-chamber with an air-escape on top extending the length of the cylinder, a series of revolving helical beaters, 110 a feeding-hopper, and an eduction for carrying off the discharge from the tail of the beaters, substantially as and for the purposes specified.

4. In a flour-dressing machine, the combination of revolving beaters and a stationary bolting-cylinder having its bottom covered with canvas and the sides and top covered with bolting-cloth, the up or lifting side being covered with finer bolting-cloth than the down side, substantially as and for the purposes specified. 115

5. The combination, in a flour-dressing machine, of the chamber I, having in its top an air-discharge, a stationary bolting-cylinder, a 125 series of revolving beaters, a feeding-hopper communicating with the cylinder, and the drop-valves F and D', substantially as and for the purposes specified.

6. The combination, in a flour-dressing ma- 130

chine, of a receiving-hopper, revolving teeth therein for disintegrating the chop or tailings, the chamber I, the stationary bolting-cylinder J, connecting therewith, a ventilating-chamber in their top, the helical beaters L L, the drop-valves F and d', the conveyers O and O', the partition e, the slides e' e', and the open-

ings e'' e'', substantially as and for the purposes specified.
